COMBINED ASHTRAY AND SIGNAL LIGHT

Colvard W. Howell, 829 E. McIntosh,
Griffin, Ga. 30223

Filed Aug. 16, 1974, Ser. No. 498,086

Term of patent 14 years

Int. Cl. D27—03

U.S. Cl. D27—15

FIG. 1

FIG. 2

FIG. 3

FIG. 1 is a perspective view of a combined ashtray and signal light showing my new design;

FIG. 2 is a rear elevational view; and

FIG. 3 is a top plan view.

I claim:

The ornamental design for a combined ashtray and signal light, as shown and described.
